(57) **CLAIM**

The ornamental design for a clear changeable tray with a built-in frame, as shown and described.

DESCRIPTION

FIG. 1 is a top perspective view of a clear changeable tray with a rectangular built-in frame, showing an embodiment of the new design;

FIG. 2 is a bottom perspective view of the new design of FIG. 1;

FIG. 3 is an exploded view of the new design of FIG. 1 from a first perspective;

FIG. 4 is an exploded view of the new design of FIG. 1 from a second perspective;

FIG. 5 is a top view of the new design of FIG. 1;

FIG. 6 is a front elevation view of the new design of FIG. 1;

FIG. 7 is a side view of the new design of FIG. 1;

FIG. 8 is a top perspective view of a clear changeable tray with a square built-in frame, showing another embodiment of the new design;

FIG. 9 is a bottom perspective view of the new design of FIG. 8;

FIG. 10 is an exploded view of the new design of FIG. 8 from a first perspective;

FIG. 11 is an exploded view of the new design of FIG. 8 from a second perspective;

FIG. 12 is a top view of the new design of FIG. 8;

FIG. 13 is a front elevation view of the new design of FIG. 8; and,

FIG. 14 is a right side view of the new design of FIG. 8. The broken lines depict portions of the clear changeable tray with built-in frame and form no part of the claimed design.
